UNITED STATES PATENT OFFICE

WALTER D. BUTZ, OF NORRISTOWN, PENNSYLVANIA, ASSIGNOR OF ONE-HALF TO
LOUIS N. D. WILLIAMS, OF ELKINS PARK, PENNSYLVANIA

STOCKING

Application filed January 17, 1928, Serial No. 247,412. Renewed March 16, 1929.

This invention relates to hosiery and has as its principal object the formation of a double gore in each side of the toe portion thereof. The double gore consists of two 5 parallel lines of tuck or other irregularly formed stitches, adapted by their relative positions and mode of production to shape the toe of the stocking in a manner to closely fit the toes of a wearer and to present a pleasing 10 appearance and symmetrical balance to the toe of a stocking, whether that stocking be knit on a circular, flat or straight knitting machine, in a seamless tubular or a flat blank form.

15 In shaping the toe of a stocking by the manipulation of the needles of the knitting machine, a line of tuck stitches is formed in each side of the toe of the stocking, which is commonly called the toe gore or suture.

20 According to the principles of my invention, I form a second line of demarcation, composed of tuck stitches, substantially parallel to this toe gore which produces what may be termed a double toe gore.

25 In tubular knit hosiery the toe gore is formed by relative reciprocal movement between the needle cylinder and the cylinder cam ring, as is well known to those familiar with the art. This gore ends abruptly at a 30 point some distance removed from the end of the stocking foot, and when the stocking is boarded the fabric between the end of the toe gore and the end of the toe of the stocking assumes a loose baggy form which is a 35 recognized objectionable feature of this type of hosiery.

I have found that by forming the second toe gore or line of tuck or other irregularly formed stitches parallel to the natural toe 40 gore and running this second gore to and ending at a point immediately adjacent the end of the toe of the stocking this objectionable baggy formation of the toe of the stocking is obviated and the toe assumes a pointed 45 formation when boarded and will closely fit the toes of a person wearing the stocking.

In some cases manufacturers of seamless tubular knit hosiery prefer to remove a portion of the foot and ankle of this type of 50 stocking to cause these portions of the stock-

ing to fit the wearer more closely. This course of procedure causes the natural gore to assume a position to one side of the center of the toe portion of the stocking, thereby giving the toe of the stocking a non-symmetrical or lopsided appearance. In such cases I position my second gore a distance away from the natural gore substantially equal to the amount of material to be removed from the foot of the stocking, thus when the stocking is completed the natural gore and the second gore are equally spaced from the opposite edges of the stocking foot, when boarded, giving the toe thereof a symmetrical balance and

Referring to the accompanying drawing:

Fig. 1 is a diagrammatic view of a portion of a stocking after boarding, embodying the features of my invention;

Fig. 2 is a plan view of the toe of a stocking embodying the features of my invention, as it is taken from the knitting machine and before being boarded, and

Fig. 3 illustrates a modification of the invention.

In practice, I prefer to form a circular knit stocking 1 in the usual manner, and at such time as the toe pocket 2 thereof is being formed I manipulate the needles of the knitting machine in a manner to produce a line of tuck stitches 3 parallel to the visible dividing line or toe gore 4 at each side of the said toe pocket 2, (see Fig. 2).

The circular knit stocking 1, after the knitting operation is completed, may be fashioned, by removing a portion along one edge thereof, and seamed along the lines 6 and 7 after the respective portions 8 and 9 thereof have been removed, for the purpose of making the stocking closely fit the foot and ankle of the wearer.

I prefer to place the line of tuck stitches 3 in a position parallel to the dividing line or gore 4 of the toe pocket 2, and spaced apart therefrom a distance which will cause the area 5 to be substantially equal in width to the removed section 8 of the original stocking foot, thus the area 5 will occupy a position in the center of the toe pocket after the

stocking foot has been seamed, as clearly illustrated in the drawings.

The fashioning of the stocking as above described, while being preferable, is not essential and, if desired, I may place a second line of tuck stitches 3^a at the opposite side of the dividing line 4, to that illustrated, for the purpose of balancing the area 5 when the stocking foot is not to be cut and seamed, as shown in Fig. 3.

Obviously my invention is applicable to either half hose or full length stockings with equal effectiveness.

In carrying out the process by which I gain the above mentioned advantages, I raise half the total number of needles in the needle cylinder (for example 130) to the inoperative or stitch-holding position. I then proceed to cause a relative reciprocating movement between the needle cams and the remaining operative needles to form the sole portion of the toe pocket in the usual manner. For each reciprocation, an additional needle at each side of the operating number of needles is thrown into the inoperative or tucking position until fifty needles have been raised to an inoperative or tucking position at each side of the operating half of the cylinder. The sixty-second needle on each side of the operating half of the cylinder is then placed in the tucking position, leaving eleven operating needles between the tucking needles, at each side of the operating half of the cylinder. On each subsequent reciprocation one of the tucking needles of the original fifty is placed in the knitting position together with the twelfth needle therefrom, which is the said sixty-second needle, and the needle immediately adjacent the said twelfth needle is raised to a tucking position causing eleven needles to be in operation between the tucking needles at all times. This operation is carried on until all the original fifty needles at each side of the operating half of the cylinder are again in the knitting position, thus a second gore is formed parallel to the first gore (Fig. 2), and when the stocking is boarded this second gore assumes a curve toward the said first or natural gore terminating in a position immediately adjacent the end of the toe pocket and in alignment with the natural gore (Fig. 1). By this method of manufacture, the loose baggy end of the toe pocket is eliminated and assumes a pointed shape which will closely fit the toes of a human foot.

The present application is a continuation, in part, of my prior application, Serial Number 137,726, filed September 25, 1926.

I claim:

1. In knit hosiery, a toe pocket having a natural gore extending longitudinally through its center on each side of said toe pocket, and a second gore comprising a line

of irregular stitches extending parallel with the said natural gore.

2. In knit hosiery, a toe pocket having a natural gore extending longitudinally through its center on each side of said toe pocket and terminating at a point removed from the end thereof, and a second gore comprising a line of irregular stitches extending parallel with the said natural gore, throughout the length of said natural gore, then curving toward the said natural gore and terminating at a point immediately adjacent the end of said toe pocket and spaced from the end of said natural gore but in alignment therewith.

3. In seamless tubular knit hosiery, a toe pocket having a natural gore extending longitudinally through its center on each side of said toe pocket, and a second gore comprising a line of irregular stitches extending parallel with the said natural gore.

4. In seamless tubular knit hosiery, a toe pocket having a natural gore extending longitudinally through its center on each side of said toe pocket and terminating at a point removed from the end thereof, and a second gore comprising a line of irregular stitches extending parallel with the said natural gore, throughout the length of said natural gore, then curving toward the said natural gore and terminating at a point immediately adjacent the end of said toe pocket and spaced from the end of said natural gore but in alignment therewith.

5. In seamless circular knit hosiery adapted to have a portion of the foot removed for the purpose of fashioning, and having a toe pocket with a natural gore extending longitudinally through its center at each side thereof, and a second gore comprising a line of irregular stitches extending parallel to said natural gore, the area between said natural and said second gores being of a width substantially equal to the width of the portion of the stocking foot to be removed in the fashioning thereof.

6. In seamless circular knit hosiery, a toe pocket having a natural gore extending longitudinally through the center of said toe pocket on each side of said toe pocket and a second gore in each side of said toe pocket comprising a line of irregular stitches extending parallel with the natural gore throughout the entire length of said natural gore which stops at a point removed from the end of the toe pocket, said second gore then curving toward said natural gore and toward the said end of said toe pocket and stopping at a point immediately adjacent the said end of said toe pocket and in line with the said natural gore but removed from the end thereof, a portion of the toe pocket being adapted to be removed adjacent one edge thereof which is substantially equal in width to the width of the area intermediate said

gores, and the areas between each gore and the adjacent edge of the finished toe pocket being substantially equal one to the other.

7. A process of forming a pointed toe pocket in seamless circular knit hosiery comprising the utilization of one half the entire number of needles normally employed in knitting the leg and foot portions of such hosiery; knitting a plurality of segmental courses of 10 stitches, progressively decreasing in length, by successively moving the needles immediately adjacent the opposite ends of said number of operating needles out of action, one at a time, until but a small percentage of said 15 needles remain in action; subsequently moving said successively withdrawn needles into action one at a time at each end of the number of operating needles; moving certain of the said operating needles, located at points 20 inwardly toward the center of said number of operating needles, successively out of action for the knitting of one segmental course and then reinserting them into activity for the formation of the next segmental 25 course of stitches in synchronism with the moving into operation of one of the inactive needles at each end of the number of active needles, and thereafter continuing the operation for successive segmental courses until the 30 entire number of pocket forming needles are again in action, to form a pair of substantially parallel gores in each side of said toe pocket one gore of each pair extending to a point immediately adjacent the outer end of 35 the toe pocket.

8. As a new article of manufacture, a seamless stocking with irregular tuck stitch lines of demarcation extending parallel to the usual sutures at opposite sides of the toe.

9. As a new article of manufacture, a seamless stocking with lines of tuck stitches extending parallel to the usual sutures at opposite sides of the toe.

WALTER D. BUTZ.
